SHOES

Max Gustin, New York, N. Y.

Application December 20, 1954, Serial No. 476,354

1 Claim. (Cl. 36—2.5)

This invention relates to shoes.

Women have a decided preference for shoes of the so-called "wedge heel" type, these being shoes which include a stiff, i. e. rigid, inflexible and unyielding, forwardly tapering broad lift that extends from the heel through the shank to the ball line of the shoe (rear end of the ball). Most women prefer to wear these shoes where style or appearance is not a factor, for example, at the beaches, the countryside and resorts. They are preferred because they feel secure and comfortable. They afford for the wearer's heel and arch a broad base which is firm, that is to say, unyielding, and thereby provide a sense of stability entirely unlike that furnished by conventional high heeled shoes in which the shank customarily constitutes leather reinforced by a steel stiffening strip. These strips are narrow and flexible and therefore are unable to supply the firm, stable support of a wedge heel type shoe.

Heretofore the use of wedge heel type shoes has been limited due to their weight and their clumsy, bulky appearance so that they are only rarely worn on formal occasions, or in sports or the office.

It is an object of my invention to provide a high heeled shoe which will afford the user the comfort, security and stability of a wedge heel type shoe but which nevertheless is graceful, slim and dainty and can be styled in any desired manner.

It is another object of my invention to provide a high heeled shoe of the character described having all of the attributes but none of the disadvantages of a wedge heel type shoe.

It is another object of my invention to provide a high heeled shoe of the character described which to outward appearances is conventional but which provides a wedge heel type support for a wearer's foot.

It is another object of my invention to provide a high heeled shoe of the character described which is of substantially conventional construction except for the incorporation of a new element which supplies a broad, rigid, firm and unyielding support for the arch and heel of a wearer's foot.

It is another object of my invention to provide a high heeled shoe of the character described which may be made at a cost for components and labor considerably less than that of a present-day conventional shoe.

Other objects of my invention in part will be obvious and in part will be pointed out hereinafter.

My invention accordingly consists in the features of construction, combinations of elements and arrangement of parts which will be exemplified in the shoe hereinafter described and of which the scope of application will be indicated in the appended claim.

In the accompanying drawings in which is shown one of the various possible embodiments of my invention,

Fig. 1 is a perspective view of a shoe constructed in accordance with the present invention;

Fig. 2 is an enlarged longitudinal central vertical sectional view through said shoe;

Figs. 3, 4, 5 and 6 are sectional views taken substantial-

2

ly along the lines 3—3, 4—4, 5—5 and 6—6, respectively, of Fig. 2; and

Fig. 7 is an exploded view of the heel and stiffener.

Referring now in detail to the drawings, the reference numeral 10 denotes a shoe embodying my invention. Said shoe includes a high heel 12, the heel herein illustrated being two inches high and having a downwardly tapering high breast face 14 and a small tread surface 16. The back 18 of the heel slants forwardly and downwardly from its top edge so that the heel in general is of conventional appearance. In addition the top surface of the heel is inclined forwardly from its back edge as is usual. Although I have shown a specific high heel, it is to be understood that high heels of any contour can be utilized, as for example, French heels, Cuban heels, Louis heels and spike heels.

Said heel is manufactured from any suitable strong, rigid and unyielding substance, the preferred material being a hard wood, and is shaped in a manner well known to the art on a standard heel-turning machine. Desirably, the grain of the wood is arranged to run in a substantially vertical direction. The heel is suitably covered, for instance, with a layer 20 of leather, fabric or plastic extending around the side and back of the wooden core and inturned to overlie the top surface thereof. In addition a layer 22 of tan sole leather extends over the breast face.

A conventional lift 24 is secured, as by tacks 26, to the tread surface of the heel.

The outsole 28 likewise is conventional, including a ball portion 30 of standard wear-resisting material as, for instance, leather, and a skived shank portion 32 which is integral with the ball portion 30 and slopes upwardly from the ball line 33 to the breast face 14 of the heel. The shank portion of the outsole and the breast face of the heel conjointly define an arch whose high point is adjacent the front edge of the heel and which, pursuant to my invention, is preferably not less than two inches high, and may be as much as four inches.

In accordance with my invention, I superpose a wooden stiffener 34 on the heel and the shank of the outsole.

The stiffener is made sufficiently thick, considering the material employed, for it to have the unyieldability, stiffness and rigidity of an ordinary wedge heel, but its thickness is kept slight so that it will be as inconspicuous as possible, and, indeed, the shoe will not at all resemble a wedge heel type shoe but will be of comparatively conventional appearance and have none of the disfiguring bulk characteristic of a wedge heel. I have found, for example, that a stiffener of hard wood (cherry) can be made as thin as about five-sixteenths of an inch without imparting any noticeably flexibility or yieldability. However, it will be understood that, if desired, the stiffener may be made somewhat, but not too much, thicker, the maximum thickness of the stiffener in accordance with my invention being five-eighths of an inch. A thickness of about one-half of an inch is shown in the drawings. This greatest thickness does not noticeably detract from the dainty, airy, light and graceful appearance of the shoe.

The width of the stiffener from front to back varies in the same manner as a conventional heel, a typical width at about the center of the shank being in the order of one and one-half inches so that it will be appreciated that the stiffener is comparatively wide and, therefore, will afford a good firm support across the full width of the wearer's foot. The stiffener runs from the back of the heel forwardly to the ball line so that it supports the wearer's foot from the ball through the arch and heel in the manner of a usual wedge shoe. The stiffener preferably is of substantially uniform thickness through the heel and rear half of the shank although, if desired, this portion of the stiffener may taper forwardly. The front half of the

stiffener tapers to a thin edge at the ball line, the material employed being such that even at this thin portion the stiffener has no noticeable flexibility and remains stiff, rigid and unyielding. The lower surface of the stiffener slopes downwardly and forwardly, conforming to the top of the heel and undersurface of the shank of the shoe.

The shank of the stiffener is not imbedded in the insole.

The grain of the stiffener preferably runs substantially parallel to the length of the shank portion as indicated by the arrow 36.

By forming the stiffener as a piece separate from the heel it can be made strong enough to take the stresses developed in the shank, the strength being due either to the selection of the wood and grain or to the other material picked for the stiffener. Moreover, the heel can be made stronger since it is not necessary as it is in a one-piece wedge compromise in orienting the grain so as to divide the strength between the heel and shank. It also should be pointed out that the increased shank strength which I have made possible is utilized to reduce the thickness of the stiffener and thereby make a shoe embodying my invention indistinguishable from a conventional shoe.

The heel of the stiffener overlies the inclined upper surface of the heel 12 and is firmly and permanently secured thereto in any suitable fashion; for example, the stiffener and heel may be vertically drilled in registration to provide bores 38, 40 which receive a hard wood dowel 42 that is glued in place. In addition, a layer 44 of glue or the like can be interposed between the juxtaposed surfaces of the stiffener and heel. Furthermore, the heel and stiffener may be tightly pressed together, as in a clamp, while the adhesive is setting, so that the forward edge of the heel bites into the undersurface of the stiffener and leaves an indentation therein which aids in preventing relative rotation of the heel and stiffener. Optionally, nails or screws also can be employed to aid in securing these two parts to one another.

For ornamental purposes, the sides of the stiffener are covered with a suitable sheet material 46 such as leather, fabric or plastic, or are painted or studded with decorative elements in a layer of adhesive lacquer or paint.

It may be mentioned that a common ornamental material can be applied to the sides of both the stiffener and heel. For instance, a single piece of leather, plastic or fabric can be cemented to the exposed sides of these two elements.

The balance of the shoe is finished with conventional elements and in a conventional fashion.

For example, as shown herein, the shoe includes an upper 48 of any desired styling and construction. The marginal edges of the upper are suitably secured to the shoe; for instance, said edges are inturned to overlie the peripheral marginal portions of the ball of the outsole and are held to the same as by adhesive. The shoe is covered from heel to toe with an insole 50 that is held in place as by a layer of adhesive 52. A conventional piping strip 54 covers the exposed edge of the insole. A thin felted pad 56 is inserted under the ball of the insole. It will be noted that the inturned edges of the upper are caught between the ball of the insole and ball of the outsole at the forward portion of the shoe and between the shank of the insole and the shank of the stiffener at the middle of the shoe, being adhesively secured to both. A conventional heel strap 58 has its marginal edge inturned between and adhesively secured to the insole and

stiffener at the shank and heel of the shoe. The insole is covered with a stocking pad 60.

My novel construction can even be employed in a formal shoe, that is to say, a shoe with a high heel having a tiny lift and a particularly thin ball outside that lends great pliability to the sole part of the shoe. When used in a shoe of this type, the stiffener despite the great flexibility of the ball of the outsole provides a solid foundation for the foot.

10 It will be seen that the construction of my shoe enables a stiff, rigid and unyielding member, the stiffener, separate from the heel, to form a part of the shoe extending from above the heel to the ball line of the outsole thereby affording the desired stable and secure support for a wearer's foot without making the shoe clumsy and bulky as in the case of a conventional wedge.

It will be appreciated that the appearance of the shoe remains dainty, graceful, light and airy and, therefore, attractive to the purchasing public. However, many tests carried out with shoes embodying my invention have proved that women consider them to feel the same as a conventional wedge type shoe.

15 It thus will be seen that I have provided a shoe which achieves the several objects of my invention and is well adapted to meet the conditions of practical use.

20 As various possible embodiments might be made of the above invention and as various changes might be made in the embodiment above set forth, it is to be understood that all matter hereinabove described and shown in the accompanying drawings is to be interpreted as illustrative and not in a limiting sense.

Having thus described my invention, I claim as new and desire to secure by Letters Patent:

25 A shoe comprising a wooden heel having a forwardly sloped upper surface, the breast of the wooden heel being at least two inches high, an outsole having a ball portion, a wooden stiffener constituting a rigid, thin, broad member which in part overlies the outsole, the portion of said stiffener which overlies the outsole being coextensive in width with the outsole, said stiffener having a heel portion fully overlying the heel with the undersurface thereof matching the upper surface of the heel and an arch outshank portion running to a forwardly extending front portion at the ball line of the outsole, said member gradually reducing in thickness from the back of the heel portion to the forward edge of the shank portion, whereby to afford a secure, stable and firm support for the arch and heel of a wearer similar to that afforded by a wedge type heel, the grain of the wood in the heel extending substantially vertically, the grain of the wood in the stiffener being sloped substantially parallel to the heel seat surface, and a vertical dowel permanently and rigidly securing the stiffener to the heel.
